UNITED STATES PATENT OFFICE.

BYRON HOLBROOK, OF MILWAUKEE, WISCONSIN, ASSIGNOR OF ONE-HALF
TO JACOB CRYDERMAN, OF SAME PLACE.

BARK-CUTTER.

SPECIFICATION forming part of Letters Patent No. 351,178, dated October 19, 1886.

Application filed December 5, 1885. Serial No. 184,801. (No model.)

To all whom it may concern:

Be it known that I, BYRON HOLBROOK, of Milwaukee, in the county of Milwaukee, and in the State of Wisconsin, have invented certain new and useful Improvements in Bark-Cutters; and I do hereby declare that the following is a full, clear, and exact description thereof.

My invention relates to bark-cutters; and it consists in certain peculiarities of construction, as will be hereinafter claimed, and more fully described with reference to the accompanying drawings, in which—

Figure 1 is a sectional view of one form of my invention, several of the knives being omitted for the purpose of clear illustration. Fig. 2 is a horizontal section on line *x x*, Fig. 1; Fig. 3, a top plan view, partly in section, of another form of my cutter; and Fig. 4, a vertical section on line *y y*, Fig. 3.

20 A represents a suitable base, designed to support my bark-cutter, and to a stringer, B, at one side beneath this base, is pivotally connected a horizontal beam, C, the free end *a* of said beam being suitably connected to a vertical adjusting-rod, D, extending up through the base and provided with a hand-wheel, *b*. The horizontal beam C is provided with a central socket, *c*, which forms a bearing for the lower end of a vertical shaft, E, said shaft car-

30 rying a series of breaker-arms, *d'*, and having keyed thereto a beveled gear-wheel, *d*, designed to mesh with a similar wheel, *e*, on a main driving-shaft, F. Secured to the vertical shaft E is a conical shell, G, preferably provided

35 with a series of slots, *f*, and a corresponding series of internal pockets, *g*, said pockets being adapted to receive the upper offset ends, *h*, of plates H. The lower ends, *h'*, of these plates are also offset, so as to fit over and 40 upon seats *f'*, formed by the solid portions of the shell at the lower ends of the slots, and at this point the parts are bolted together, as shown at *i*. The several plates are each provided with horizontal slots *h*², through which

45 pass bolts *k*, having their heads countersunk in external knives, I, this construction and connection of the parts permitting of an adjustment to vary the cut, as well as to compensate for the wear upon said knives. To 50 further vary the cut of the knives I, the plates H are notched at suitable intervals, and provided with adjusting-screws *h*², designed to

bear upon said knives, the said screws serving to force the cutting-edges of the knives out (more or less) from the surfaces of the plates 55 H, so as to increase or lessen the depth of cut of said knives. The conical shell G is surrounded by stationary shell K, suitably secured to the base A, and this latter shell has its lower portion constructed similarly to that 60 of the former, and secured thereto in the manner above described are plates L and knives M, the same in construction as those secured to said shell G. By the above-described construction and relative connection of the knife-plates H L with their respective shells G K any one or all of said plates may be readily removed, should at any time such removal be found necessary or convenient.

It will be noticed that the knives I of the 70 shell G are externally arranged, while those, M, of the shell K are arranged upon its interior, but with their cutting-edges disposed in opposition to said knives on the former shell, a sufficient bark-space, *m*, being left between the respective parts. The shell G has its upper or solid portion provided with external breaker-arms, *n*, while the shell K is provided at its inner upper portion with similar arms, *o*.

Bolted to the base A and shell K so as to leave a bark-space, *p*, is a casing, N, and secured to an outwardly-projecting flange, *q*, at the upper end of said shell, is the flanged bottom portion, *r*, of a hopper, O, the latter having secured upon its interior breaker-arms *s*.

In Figs. 3 and 4, instead of the conical shell G, I employ a cylindrical shell, P, provided with slots, and having secured thereto plates R and adjustable knives S, the construction 90 and connection of these parts being similar to those attached to said shell G. This cylindrical shell P has upon its interior, near each end, a series of spokes or braces, *t*, radiating from sockets *u*, adapted to fit upon the vertical shaft E, so that said cylinder may be revolved therewith. In this form of my bark-cutter the shell P is surrounded by a cylindrical casing, T, cut out at its upper front portion to register with the feeding-trough U. This casing is provided upon its interior with a series of angular projections, *v*, arranged at suitable intervals, and having adjustably secured thereon knives V, the cutting-edges of

which are disposed in opposition to those on the cylindrical shell P, and said casing and shell are so arranged with relation to each other as to leave between them a bark-space, v'. Extending across the trough U, near its inner end, is a corrugated roller, w, one end of which is journaled in a side of said trough, the other end being reduced and extended to revolve in a bearing, w', and has keyed thereto a band-pulley, w'', and journaled in bearings w''' in front of the roller w, on each side of the trough, are short corrugated rollers z, said rollers being employed to feed the bark to the knives upon the revolving cylindrical shell P.

15 In the operation of the first form of my invention, bark, being introduced into the hopper O, is subjected to the action of the breaker-arms d' and s, and by them reduced. The reduced bark is carried down between the conical revolving shell G and the stationary one, K, and is further reduced by the action of the breaker-arms n o, projecting from the respective shells. After being thus reduced the bark continues down and accumulates in the space 25 m, where it is subjected to the action of the knives I M on the conical revolving shell G and stationary shell K, these knives operating to shave the bark, the chips or shavings therefrom passing through the slots in said shells 30 and falling to the floor or a suitable receptacle below the supporting-frame A of the machine. The bark-space m may be increased or lessened accordingly as the horizontal beam C may be adjusted by the vertical rod D, and this adjusting means may be also employed to throw 35 the driving mechanism out of gear, it being only necessary to depress said beam a sufficient distance to bring the gear-wheel d on the shaft E out of mesh with the gear e on the driving-shaft F.

The operation of that form of my invention shown in Figs. 3 and 4 is virtually the same as that shown by Figs. 1 and 2 and above described, with the exception that the bark is fed from the trough U by the corrugated rollers w z directly to the knives upon the revolving cylindrical shell P, and the shavings from said bark pass through the slots in said cylindrical shell and fall to the floor or receptacle. 45 Such particles of bark as may escape the action of the revolving knives are carried on into the space v', between the cylindrical shell P and casing T, and as it accumulates to fill said space the mass is acted upon by said revolving knives and the stationary ones, V, upon the interior of the casing, the cutting-edges of the respective knives being oppositely arranged, as above described.

By my device the bark is planed into chips 60 or shavings of any desirable grade, and by the peculiar arrangement of the knives they act on both sides of the mass of bark, thereby facilitating the operation of reducing bark, and the substance thus reduced is left in the best possible condition for the extraction of its tanning properties.

Having thus fully described my invention,

what I claim as new, and desire to secure by Letters Patent, is—

1. In a bark-cutter, the combination of an outer shell, a series of knives suitably secured to the inner face of said outer shell, an inner shell provided with a series of slots that extend in the direction of its length, a corresponding series of knives suitably secured to the inner shell and having their cutting-edges projected outwardly therefrom, and means for revolving said inner shell in a direction opposite to the cutting-edges of the knives on the outer shell, substantially as and for the purpose set forth. 80

2. In a bark-cutter, the combination of an outer shell provided with a series of slots that extend in the direction of its length, a corresponding series of knives suitably secured to said shell and their cutting-edges arranged to project inwardly therefrom, an inner shell also provided with a series of slots similar to those in the outer shell, a corresponding series of knives suitably secured to the latter shell and having their cutting-edges projected outwardly therefrom, and means for revolving this inner shell in a direction opposite to the cutting-edges of the knives on the outer shell, substantially as and for the purpose set forth. 95

3. In a bark-cutter, an outer shell provided with a series of slots that extend in the direction of its length, a corresponding series of removable plates secured to said outer shell, and a series of adjustable knives in turn secured to the plates, in combination with an inner shell also provided with slots similar to those in the outer shell, a corresponding series of plates secured to the inner shell, a series of adjustable knives in turn secured to the latter plates and arranged to have their cutting-edges in opposition to those of the knives on said outer shell, and means for revolving said inner shell, substantially as and for the purpose set forth. 100

4. In a bark-cutter, the combination, with means for reducing the bark, of an outer shell, a series of knives secured to said shell and having their cutting-edges arranged to project inwardly therefrom, an inner shell provided with a series of knives having their cutting-edges arranged to project outwardly therefrom, and means for revolving this inner shell in a direction opposite to the cutting-edges of the knives on the outer shell, substantially as and for the purpose set forth. 115

5. In a bark-cutter, an outer shell provided with a series of slots that extend in the direction of its length, a corresponding series of external pockets, a series of plates offset at their ends and secured to this outer shell, and a series of knives in turn adjustably secured to the plates, in combination with an inner shell provided with slots similar to those in the outer shell, internal pockets, a series of plates, also offset at their ends and secured to the inner shell, a series of knives in turn adjustably secured to these latter plates and arranged to have their cutting-edges in oppo- 125 130

sition to those of the knives on said outer shell, and means for revolving said inner shell, substantially as and for the purpose set forth.

6. A bark-cutter comprising a hopper provided with interior breaker-arms, a vertically-adjustable shaft, also provided with breaker-arms, an inner shell secured to the shaft and provided with exterior knives and breaker-arms, an outer shell provided with interior breaker-arms and knives, the latter arranged to have their cutting-edges in opposition to those of the knives on the said inner shell, a

casing surrounding said outer shell, and a supporting-base, substantially as and for the purpose set forth. ¹⁵

In testimony that I claim the foregoing I have hereunto set my hand, at Milwaukee, in the county of Milwaukee and State of Wisconsin, in the presence of two witnesses.
